UNITED STATES PATENT OFFICE.

ADOLPH BAYLER, OF BROOKLYN, NEW YORK, ASSIGNOR TO THOMAS ADAMS, SR., OF BROOKLYN, NEW YORK.

WRAPPING-MACHINE.

SPECIFICATION forming part of Letters Patent No. 693,099, dated February 11, 1902.

Application filed June 14, 1901. Serial No. 64,622. (No model.)

To all whom it may concern:

Be it known that I, ADOLPH BAYLER, a citizen of the United States, residing at Brooklyn, in the county of Kings and State of New York, 5 have invented certain new and useful Improvements in Wrapping-Machines, of which the following is a specification.

My invention pertains to machinery for wrapping gum, chocolate, and other commodities, and has reference particularly to certain features or parts of a machine of this character set forth and described in an application filed in the name of Thomas Adams, Sr., on the 31st day of August, 1900, and designated by Serial 15 No. 28,678. The improvements relate particularly to the mechanism for actuating the nippers or gripping devices by which the paper strip from which the wrappers are cut is drawn forward.

20 In the particular work for which the machine above noted was primarily designed an inner wrapper of paraffined paper and an outer wrapper bearing certain printed matter or devices are employed. The printed matter 25 is repeated a number of times on each strip from which the outer wrappers are cut, and in order that each wrapper may bear its full legend or device and not cut into or carry a portion of that belonging to the next wrap- 30 per it is essential that the strip be advanced a definite distance each time. Owing to atmospheric changes and to the hygroscopic na- 35 ture of paper it is found in practice that in some weather the strip elongates and in other weather contracts. As a consequence the wrapper-blanks cut therefrom are not always severed on the proper lines between successive designs or printed forms. In some other cases where the strip is elongated it happens 40 that after several blanks have been cut the printed matter or design thereof will be partially clipped or cut off, while when the strip contracts there will sometimes be one entire design or form and a small portion of another 45 on the same blank. To obviate this difficulty, I provide means for varying the throw of the lever by which the grippers are operated, so that while going always to a given point to grasp the forward end of the wrapper-blank 50 they shall be caused to move therefrom a greater or less distance, according to the at-

mospheric conditions and the consequent condition of the wrapper material.

Another serious difficulty encountered in the practical operation of machines of this 55 general class resides in the liability of the blades or members of the cutting devices to play slightly or get out of alinement, and consequently to produce a ragged or tearing cut. To obviate this difficulty, I guide the two mem- 60 bers and the actuating-lever of the cutting device in ways, and I provide a yielding pres- 65 sure-plate to press and hold one blade in close contact with the other. The construction of parts whereby I attain these ends is repre- 70 sented in the accompanying drawings, in which—

Figures 1 and 2 are sectional elevations showing the grippers and their actuating mechanism and also the adjusting devices to 70 which the present invention pertains; Fig. 3, a sectional view of the actuating-lever and its supporting and adjusting devices; Fig. 4, a view of the actuating-lever and its adjusting devices looking from the opposite face from 75 that seen in Figs. 1 and 2; and Figs. 5 and 6, elevations of the cutting devices and their ac- 80 tuating mechanism, the bed or table upon which the cutter is mounted being shown in section.

Referring first to Figs. 1, 2, 3, and 4, A represents the bed or table of the machine; B, a trough in and through which the strip of pa- 85 per or other material from which the wrap- 90 per is formed is fed. This strip is first ad- 95 vanced along the trough until its forward end encounters a cutting knife or blade C, which rises from beneath and passes through an opening in the bed or table B, coacting just above said bed or table with a blade D and plate E, the latter urged and held toward the blade D by spring a, encircling a screw-stem b, which passes through a hole or opening in the blade D and screws into the plate E, the spring a being interposed between the head 100 of the screw b and the blade D. These parts will be more fully described later on. When the parts C and D separate, nippers F, com- 105 prising a fixed blade c and a pivoted blade d, advance toward the delivery end of the trough B and grasp the protruding end of the paper or wrapper strip. As the construction and

operation of the nippers themselves constitute no part of my invention, but are set forth at length in the application of Thomas Adams, Sr., above mentioned, it is unnecessary to make further description of the same herein. G indicates an upright lever, which is connected by a link II with a lug on the under side of the gripper or the slide which carries the gripper. This lever G is at its lower end carried by a pivot-bolt I, which passes eccentrically through a circular boss or hub e of a rocking block or yoke J. The circular hub or boss e of the yoke J is accurately fitted in a block or standard K, which constitutes a bearing for said boss and which also has a foot or base plate to give steadiness and bearing for the standard upon the base or bed of the machine. The foot or base plate of the standard K is slotted, as shown at f, Figs. 3 and 4, to receive the lower end of the lever G and preclude displacement thereof. As shown in Figs. 1, 2, and 4, the yoke J is formed with two upwardly-extending ears, which project from one face of the yoke into line or plane with the upright portion of standard K. These lugs or ears are tapped to receive thumb-screws L, which, bearing against opposite edges of the standard and being turned one forward and the other backward, serve to adjust the yoke or to swing it about the axis of the circular boss or hub e. The yoke J is slotted, as shown at g, to receive a binding-screw or tap-bolt M, which, passing through said slot and entering a hole tapped in the standard, serves to bind the yoke to said standard and to hold it in its adjusted position. As the bolt I, which constitutes the pivot of lever G, is eccentrically located in the hub or boss e, it follows that as the yoke J is rocked the position of the said pivot-bolt I will be varied. With the yoke in its medial position—that is, with its ears equidistant from the standard K—the pivot-bolt I will under the preferred arrangement of parts occupy a position vertically beneath the center of the boss e. Hence upon rocking the yoke J to one or the other side the axis of the bolt I, and consequently the pivotal axis of the lever G, will be thrown slightly to one or the other side of a vertical line passing through the center of the hub or boss e. This will of course vary the distance to which the lever G will be thrown in one or the other direction. In approaching the strip the nippers, which are at the moment open, may move a slightly greater or less distance without affecting the final result, as they will simply seize the paper a little nearer to or farther from the end of the trough or guide B; but the outward or backward movement of the nippers must be in exact proportion to the length of blank or wrapper required. By shifting the pivot or fulcrum of the lever G in the manner above described this result is accurately and certainly attained. The thumb-screws L afford means for accurately effecting the adjustment

and for temporarily holding the parts until firmly clamped by the screw or bolt M.

In practical operation this device is found to meet and answer perfectly the conditions above stated and to enable the operator readily to adjust his machine according to all variations of atmospheric conditions.

Figs. 1 and 2 show the yoke and the pivot for the lever in the medial adjustment. Fig. 4 shows it shifted to one side of the center of the hub or boss e, as shown by the relation of the pivot-pin to the dotted line passing vertically through the axis of said boss or hub.

Referring now to Figs. 5 and 6, illustrating the cutting mechanism of the machine, which, as before indicated, coöperates with the gripper devices, the improvements therein will be explained. Secured to or formed upon the under side of bed or table A are vertically grooved or slotted guides h, in which moves a slide N, which carries the lower blade or cutting member C and which is reciprocated vertically by an elbow-lever O, fulcrumed in or upon a lug depending from bed or table A and furnished with a stud or bowl i, which extends into a cam-groove j in a rotary cam wheel or disk P. On the upper side of the table A are standards k, having horizontally-projecting ears or brackets l, both of said standards being slotted or bifurcated at their upper ends, one to receive the pivotal end of a lever Q and the other to guide the free or moving end thereof. A pin m, passing through the upper end of one of the standards k and through lever Q, forms a fulcrum or pivot therefor. The guiding of the free or moving end of the lever Q in the slotted post or standard k is important for the reason that it is thereby given a straight-line movement and is precluded from exerting any lateral or tipping strain upon the upper cutting blade or member D, to which it gives motion. The upper blade or member D is extended lengthwise beyond the limits of the lower blade C, and the extensions are vertically bored or perforated to fit closely about vertical guide-rods n, the lower ends of which are seated in the bed or table A of the machine, while the upper ends are held in the projecting lugs or brackets l of the standards k. This makes a firm and rigid construction and insures the true vertical movement of the blade or member D. Notwithstanding this guidance of the blades or cutting members, there is in practice slight lateral play thereof, incident to the requisite freedom of movement or to the play occasioned by slight wear of the guiding-faces. It is found that even the minute play thus occasioned is very liable to result in a ragged cut or in the tearing of the strip which the cutter is designed to sever. To completely guard against this, there is applied to the rear face of the cutter D a pressure-plate E, which is preferably connected by a hinge o, as shown in Figs. 1 and 2. This pressure-plate is normally drawn to-

ward the cutter D by a spring *a*, encircling a screw-threaded stem *b*, which passes through an opening in the cutter D and is screwed into the plate E, as shown in said figures.

5 The spring *a*, encircling the stem *b* and lying between the front face of cutter D and the head of the stem *b*, tends constantly to draw the plate E into close contact with the blade D, and the degree of pressure may be varied, 10 as desired, by advancing or backing the screw-stem *b*. The inner face of the plate E is beveled slightly from the lower edge upward, as seen in Figs. 1 and 2, to insure proper entrance of the thin cutting edge of the lower blade C.

15 The construction thus described insures close contact of the proximate faces of the upper and lower cutters D and C and the consequent clean severance of the strip, the plate E yielding to permit the cutter C to rise to its proper 20 height relatively to cutter D and between it and the plate E. The plate E serves the further purpose of a presser-foot to prevent the wrapper-strip from being carried upward past the lower edge of the cutter D. Connection is 25 made between the lever Q and the cutter D by means of a short link T, suitably pinned to the respective members, as indicated, this connection affording sufficient play between the lever and the cutter to prevent 30 cramping or binding of the latter, while leaving it free to follow a true vertical path. The lever Q is raised and lowered through the medium of a lever U, fulcrumed in a post or standard V in the base or bed of the machine 35 and having one end connected by a rod or link W to the lever Q, its other end being provided with a stud or bowl *r*, which, projecting into a cam-groove *s* in the wheel or disk P, is given the requisite vibration. The grooves 40 *j* and *s* of the cam wheel or disk P are of course fashioned with due reference to each other and to the movements to be given to the respective blades or members and are such as will insure a simultaneous descent of 45 the upper blade or member and rise of the lower blade or cutter. Preferably the lower blade will be caused to withdraw before the upper member rises from its cutting position, but this is not essential.

50 Vibratory motion is imparted to lever G, which actuates the nippers, by means of a cam - wheel X, the periphery of which is grooved to receive a stud or bowl *t*, projecting from the lever, as indicated in Figs. 1 and 2.

55 Features illustrated in the drawings but not herein described are not of my invention, and hence need not be further referred to, nor have I deemed it necessary to show the 60 entire machine, since the features here shown and described may be sufficiently explained and fully understood without encumbering the description with matters not original with myself.

65 The embodiment of the invention herein set forth is deemed the best of several forms in which it may be made; but it is to be un-

derstood that the adjustable pivot I may be modified as to its mode of adjustment without departing from the general lines of my 70 invention. So, too, the cutter may have its guides varied in form, and the plate E may be otherwise attached to the upper blade B, provided only it be held thereto by spring-pressure and be left free to move therefrom 75 to the extent necessary to admit the blade C.

Having thus described my invention, what I claim is—

1. In a packing or wrapping machine, the combination with a trough or guide for the 80 wrapper-strip, of nippers or gripping devices movable toward and from said trough; a vibratory lever connected with and serving to give motion to said nippers; a cam for imparting vibratory motion to said lever; and 85 an adjustable fulcrum for the lever whereby the path and range of movement of the lever may be varied.

2. In combination with a trough or guide for a wrapper-strip, a cutting device arranged 90 in the path of said strip and serving to determine the position of the forward end of the strip; nippers movable toward and away from the trough or guide; a vibratory lever connected with and serving to move said nippers; 95 a cam for vibrating said lever; and an adjustable pivot for said lever, comprising a supporting-block, a circular member rotatable in the supporting-block, and a pivot-pin eccentrically mounted in said rotary block, 100 substantially as and for the purpose set forth.

3. In a machine for wrapping merchandise, the combination of a wrapper-guide; nippers movable toward and from said guide and serving to draw the wrapper-strip therefrom; a 105 vibratory lever connected with and serving to move the nippers; a cam adapted and arranged to vibrate said levers; a post or standard provided with a circular seat; a yoke provided with a circular boss to fit the seat in the standard, and with separated arms or ears; adjusting-screws carried by said ears and arranged to bear against opposite sides of the standard; and a pivot-pin eccentrically mounted in the circular boss of the yoke, substantially as and for the purpose set forth. 115

4. In combination with a suitable bed or support, and with a trough or guide for a wrapper-strip; nippers F movable toward and from said guide; a vibratory lever G connected with and serving to move said nippers; a cam X for vibrating said lever; a standard K provided with a circular opening; a yoke J provided with a circular hub or boss *e* to fit said opening, and with perforated ears; screws L applied to said ears and arranged to bear against the standard K; a pivot-pin I passing eccentrically through the circular hub or boss *e*; and a clamping or binding screw M passing through the yoke and into 120 the standard K. 125

5. In a wrapping-machine, the combination of a guide for a wrapper-strip; a cutter arranged across the path of said strip; nippers

movable toward and from said cutter; a lever for moving said nippers; and an adjustable fulcrum for said lever whereby the throw or path of said lever, and consequently of the nippers, may be varied according to variations in the length or condition of the wrapper-strip.

6. In a wrapping-machine, the combination of a suitable bed or support provided with a pathway or guide for a wrapper-strip; and a cutter for said strip, comprising an upper blade or member, a lower blade or member, and a pressure-plate carried by the upper member and held thereto by spring-pressure, substantially as and for the purpose set forth.

7. In a wrapping-machine, the combination with a bed or wrapper-support; of a cutter, comprising vertical guides, upper and lower cutting members carried by said guides, and a pressure-plate carried by one of the cutter members and adapted to direct the other cutter member into and to hold it in close facewise contact with the companion cutter member.

8. In a wrapping-machine, the combination with a suitable bed or support; of slotted posts or standards *k* provided with brackets or projections *l*; guiding rods or stems *n* extending from the brackets to the bed; cutter

D having perforated ears to fit said stems; *30* lever *Q* fulcrumed in one of the standards *k* and guided by the other; and a coacting cutter-blade, all substantially as shown and described.

9. In a wrapping-machine, the combination *35* of a bed or table; nippers for advancing a wrapper-strip a predetermined distance over said table; a lever connected with the nippers and serving to move the same; a cam for actuating said lever; an adjustable fulcrum *40* for the lever; a cutter arranged across the path of the wrapper-strip, and comprising an upper and a lower member; a pressure-plate carried by one of said members and serving to hold the two cutters in close contact; levers *Q* and *U* and connecting-rod *W* for actuating the upper cutter member; elbow-lever *O* for actuating the lower cutter member; and a cam wheel or disk *P* for imparting motion to the levers *O* and *U*.

In testimony whereof I have signed my name to this specification in the presence of two subscribing witnesses.

ADOLPH BAYLER.
